UNITED STATES PATENT OFFICE.

WILLIAM D. SARGENT, OF EVANSTON, ASSIGNOR TO THE CONGDON BRAKE SHOE COMPANY, OF CHICAGO, ILLINOIS.

BRAKE-SHOE.

SPECIFICATION forming part of Letters Patent No. 416,379, dated December 3, 1889.

Application filed September 28, 1889. Serial No. 325,372. (No model.)

To all whom it may concern:

Be it known that I, WILLIAM D. SARGENT, a citizen of the United States, residing at Evanston, in the county of Cook and State of Illinois, have invented a new and useful Improvement in Brake-Shoes, of which the following is a specification.

My invention relates to brake-shoes for railway-cars wherein the brake-beam is hung from the body of the car instead of from the truck; and the class of brake-shoes to which my improvement is applied is that in which both the flange and the tread of the wheel are engaged by the shoe. A common difficulty encountered with brake-shoes of this character, when hung in the manner described, is that owing to the lateral swinging of the brake-beam, which carries the shoe, or the partial rotation of the car-trucks in their axes in passing over curves in the track, which tends to throw the wheels out of line with the brake-shoes, little reliance can be placed upon the existence of a proper alignment between the flange of the wheel and the recess in the shoe formed to receive it at the instant when the brakes are applied. As a result, the flange of one wheel is liable at any time to pass wholly outside the confines of its adjacent shoe and the flange of the other wheel at the same time to meet the tread portion of its adjacent shoe. The effect of this is obviously not only to impair the effectiveness of the brakes upon the wheels at the time when the inaccuracy occurs, but also to produce unequal and highly injurious wear upon the brake-shoes.

The difficulty above mentioned is completely overcome by means of my invention, which is illustrated in the accompanying drawings, in which—

Figure 1 is a rear view of a brake-shoe provided with my improvement; Fig. 2, an inner side elevation of the same, and Fig. 3 a cross-sectional view taken on the line 3 3 of Fig. 2 and viewed in the direction of the arrow.

A is the brake-shoe, having the usual tread-bearing portion *t*, flange-bearing portion *s*, and flange-lip *r*. Upon the flange-lip and projecting therefrom in a direction substantially at right angles with the tread of the shoe, and preferably in about the median line of the shoe, is an extension *B* of the flange-lip, of sufficient length to extend to a point

within the periphery of the wheel-flange 55 when the brake-shoe is at its greatest distance from the wheel. This extension should preferably be made of wrought-iron, malleable iron, or steel, and I prefer to make it in the form of a bolt cast into the flange-lip. 60 For this purpose the flange-lip is cast with a projection *q*, inclosing the extension, which may be roughened or barbed, as represented at *p* in Fig. 3, to increase the hold upon it of the metal. At the base of the projection a 65 boss *o* may be formed with advantage in the casting around the extension *B*.

When the brake-shoes are placed in position upon the brake-beam, the extension *B*, by projecting within the peripheries of the 70 wheel near the sides of the wheel-flanges, serve to limit the lateral throw of the brake-beams, so that the wheel-flanges must at all times be nearly in alignment with the recess in the flange-bearing. When the brakes are 75 set, the extension operates as a guide, bringing the wheel-flange into the recess of the shoe, and in this it is aided by the rounded boss *o*. Of course the extension *B* is not necessarily cylindrical, but may be of any 80 suitable and convenient form, and obviously more than one may be formed upon each flange-lip, if preferred.

What I claim as new, and desire to secure by Letters Patent, is— 85

1. The combination, with a brake-shoe *A*, having a flange-lip *r*, of a metal extension upon the flange-lip, substantially as described.

2. In combination with a brake-shoe *A*, 90 having a flange-lip *r*, the metal extension *B*, cast into the flange-lip, substantially as described.

3. In combination with a brake-shoe *A*, the flange-lip *r* thereof formed with a projection 95 *q*, and the bolt *B*, cast within the said projection and forming an extension of the flange-lip, substantially as described.

4. In combination with a brake-shoe *A*, the flange-lip *r* thereof formed with a projection 100 *q*, provided with a boss *o*, and bolt *B*, cast within the projection *q* and forming an extension of the flange-lip, substantially as described.

WILLIAM D. SARGENT.
